UNITED STATES PATENT OFFICE.

CHARLES NEWTON WOODS, OF FINDLAY, OHIO.

CAN OPENER.

Application filed September 29, 1924. Serial No. 740,558.

To all whom it may concern:

Be it known that I, CHARLES NEWTON Woods, a citizen of the United States, residing at Findlay, in the county of Hancock 5 and State of Ohio, have invented a new and useful Can Opener, of which the following is a specification.

This invention relates to a can opener, one of its objects being to provide a simple 10 form of device which, with one stroke, will cut out one end of a can, leaving the edges of the opening inturned so that they will not present rough jagged portions liable to injure the user of the can.

15 A further object is to provide a device of this character which is simple in construction, easy to operate and which can be adjusted for use in connection with cans of different diameters.

20 With the foregoing and other objects in view which appear as the description proceeds, the invention resides in the combination and arrangement of parts and in the details of construction hereinafter described 25 and claimed, it being understood that changes in the precise embodiment can be made within the scope of what is claimed without departing from the spirit of the invention.

30 In the accompanying drawings the preferred form of the invention has been shown.

In said drawings—

Figure 1 is a front elevation of the device, a portion thereof being shown in section.

35 Fig. 2 is a section on line 2—2, Fig. 1.

Fig. 3 is a section on line 3—3, Fig. 1.

Referring to the figures by characters of reference 1 designates opposed arcuate plates preferably formed of this sheet of 40 steel. Each plate is provided with downwardly converging cutting edges 2 coming together to form a point 3. Extending radially from the upper edge of each plate are stop plugs 40 and projecting upwardly 45 from the middle portion of each plate is an arm 5. One of these arms is extended laterally at its upper end to form a tongue 6 while the other arm 5 is extended laterally and has inturned side portions 7 forming 50 a channel 8 adapted to receive the tongue 6.

In using this device the tongue 6 is adjusted within the channel 8 until the dis-

tance between the opposed arcuate plates 1 is slightly less than the diameter of the can to be opened. The points 3 are then 55 placed against the end of the can at diametrically opposed points after which the entire device is pushed downwardly forcibly. This will drive the points 3 into the can and the upwardly diverging edges 2 of the 60 plates 1 will cut into the can and produce arcuate openings. In practice it is intended that the upper portion of the opposed plates will be so that during the completion of the downward stroke of the can opener the opposed arcuate cuts formed thereby will come together, thereby entirely separating the 65 end of the can from the wall thereof. The lugs 4 limit the movement of the opener into the can.

70 It will be obvious that the device is very simple, durable and efficient and can be operated readily. As the opener cuts the can during the downward stroke, the edges produced by the cut are turned inwardly so 75 that there is no danger of injuring the user.

What is claimed is:—

1. A can opener including opposed arcuate cutting plates, each having a point at 80 one end and cutting edges diverging from the point, and an adjustable connection between the plates constituting a handle.

2. A can opener including opposed arcuate cutting plates, each having a point at one end and cutting edges diverging from the point, an adjustable connection between the plates constituting a handle, and means 85 on the plates for limiting their movement in one direction during the cutting operation.

3. A can opener including opposed arcuate plates, each having a point at one end and cutting edges diverging from the point, those ends of the plates remote from the 90 points normally lapping at their sides, arms extending from the respective plates, a tongue upon one of the arms, a channeled member upon the other arm slidably engaged by the tongue, said member, tongue and arms constituting a handle.

4. A can opener including opposed arcuate plates, each having a point at one end and cutting edges diverging from the point, those ends of the plates remote from the 95

points normally lapping at their sides, arms extending from the respective plates, a tongue upon one of the arms, a channeled member upon the other arm slidably engaged by the tongue, said member, tongue and arms constituting a handle, and stop lugs upon the plates.

In testimony that I claim the foregoing as my own, I have hereto affixed my signature in the presence of two witnesses.

CHARLES NEWTON WOODS.
